(57) **CLAIM**

The ornamental design for a lighted artificial twig branch with micro LED, as shown and described.

DESCRIPTION

FIG. 1 is a front perspective view of a lighted artificial twig branch with micro LED, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged top plan view thereof;

FIG. 8 is an enlarged bottom plan view thereof;

FIG. 9 is an enlarged view of a portion labeled, "FIG. 9", in FIG. 7; and,

FIG. 10 is an enlarged view of a portion labeled, "FIG. 10", in FIG. 8.

The dash dot dash lines in FIGS. 7-10 are for the purpose of depicting the cut line of the enlarged views and form no part of the claim. The dashed broken lines in the figures illustrate portions of the article that form no part of the claimed design.
